HOYT CATLIN, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC APPLIANCE.

1,408,268.

Specification of Letters Patent. Patented Feb. 28, 1922.

Application filed March 26, 1920. Serial No. 368,952.

To all whom it may concern:

Be it known that I, HOYT CATLIN, a citizen of the United States of America, residing at Bridgeport, in the county of Fairfield and State of Connecticut, have invented 5 certain new and useful Improvements in Electric Appliances, of which the following is a specification.

My invention relates to electric appliances, 10 and particularly to a terminal block and switch adapted for use with such portable heating units as electric grills or the like, the object of my invention being to provide a construction which affords a terminal 15 block adapted to be mounted on the heating appliance and an independent switch base adapted to be assembled thereon and to operate therewith to control the current to the heat units of the appliance.

20 In the accompanying drawings—

Fig. 1 is a side elevation of an electrical grill showing a switch mounted thereon in accordance wth my invention;

Fig. 2 is a plan thereof;

25 Fig. 3 is an inverted plan of a switch base.

Fig. 4 is a perspective of a connection block;

Fig. 5 is a vertical section on the line 5—5,

30 Fig. 6;

Fig. 6 is a vertical section on the line 6—6,

Fig. 1;

35 Figs. 7, 8 and 9 are diagrams of the switch connections.

While the present invention may be readily adapted to heating appliances of various sorts, I have shown it embodied in an electric grill or toaster. The latter comprises, as usual, a top ring frame 10, with reticulated area 11, supported by standards 12 upon the base 13. Beneath the reticulated plate 11 are arranged the resistance units 14 and 15, here shown as concentric coils. At 40 a suitable point, 16, the ring frame 10 is apertured to receive an insulating block 17 having an arcuate shoulder 18 adapted to fit against the curved outer face of the ring. Upon the inner face of this block is mounted 45 a group of terminals 19, 20, 21 and 22 adapted to receive an insulating block 17 having an arcuate shoulder 18 adapted to fit against the curved outer face of the ring. Upon the inner face of this block is mounted a group of terminals 19, 20, 21 and 22.

50 adapted to make connection with the end leads 23, 24, 25 and 26 of the resistance coils 14 and 15. These terminals may be of any suitable character, but as here shown they comprise binding screws which take 55 into tapped hollow rivets 27 passing through

the block 17, and tapped at the outer face of the block. A strip 28 engaged beneath the heads of the rivets of the terminals 21 and 22 serve to electrically connect the latter. While any suitable securing means may be 60 provided for holding the block 17 in position in the ring 10, I have found its engagement with the leads 23 to 26 from the heater coils sufficient to anchor it until the cooperating switch has been mounted upon the appliance, 65 the switch serving to firmly hold the block in proper position.

To this end the switch base 29, which lies against the upright 12 in assembled position, 70 is provided with an extension 30 adapted to overlie the block 17, the flange 31 bearing against the ring 10 and being secured thereto by bolts 32. The lower face of the extension is recessed at 33 to snugly receive 75 and hold the block. Leading to the recess 33 are spring straps 34, 35 and 36, the ends of which register, in assembled position of the parts, with the tapped rivets 27 of the terminals 19, 20 and 22, to which they are secured by screws 37 passed through holes 80 38 in the base. The opposite ends of the straps are connected by bolts 39 with the switch terminals 40, 41 and 42.

The switch mechanism controlling the distribution of the current may be of any suitable type. I have here indicated a rotary snap switch housed within the cover 43, but not shown in detail since it is of generally well known type, and to the details of which my invention does not relate. It suffices to 85 point out that the wire mains 44 and 45 are respectively connected to the switch terminals 41 and 46, and that the switch blades and terminals are so arranged as to effect 90 the distribution of the current through the coils 14 and 15 in such manner as to give high, medium and low heats (Figs. 7, 8 and 9), as well as to cut off current completely 95 from the coils. The wires are led to the switch through an entrance channel 47 100 formed in the lower face of the base, and branch channels 48 and 49 extending therefrom to the switch terminals 41 and 46 respectively.

The construction described has the advantage of affording a connection block to which the heating units may be connected at the factory where the appliance is made, leaving the switch as an independent element 105 to be applied by the installing electrician 110

when the device is assembled for use. The switch is thus protected during transportation and is less likely to be injured. The connections from the grill wires to the block 5 are readily made, while the connections from the switch base to the block are effected without possibility of error, since the switch base will fit the block in only a single position. The mounting of the connection block 10 17 freely in the ring 10 of the grill permits the block to be made of such size that it will adapt itself to the hole 16 in the flange 10 with some play, and thus accommodates itself to slight variations, both in the size of 15 the block and of the hole. Similarly, the spring straps 34, 35 and 36 are sufficiently flexible to yield somewhat, and thus to accommodate themselves to variations in the base 29, or in the block 17, incidental to their 20 manufacture. Where the block 17 and base 29 are made of porcelain, it is impossible to avoid some variation due to unequal shrinkage in baking. I prefer, however, to mold both block and base out of a suitable insulating composition, since greater accuracy 25 of fit is thereby secured. The support of the switch block by the screw bolts 32 is sufficient, in view of the fact that the base of the switch rests against the standard 12, 30 and is supported at this point as well.

Various modifications in detail of construction will readily occur to those skilled in the art, which do not depart from what I claim as my invention.

35 I claim—

1. A switch for electric heating appliances comprising a connection block, terminals thereon for the resistance coils of the heating appliance, means for mounting said block on the heating appliance, in combination with an independent switch base, means for mounting the same upon said appliance in assembled relation to said terminal block, and means for establishing electrical connection 40 between the terminals on the block and the terminals of the switch.

2. A switch for electric heating appliances comprising a connection block, terminals thereon for the resistance coils of the heating 45 appliance, means for mounting said block on the heating appliance, in combination with an independent switch base having an extension adapted to overlie and embrace said terminal block, straps extending beneath said base, and means for connecting the same on the one hand to the terminals of the switch, and on the other hand to the 50 terminals of the block.

3. A switch for electric heating appliances 55 comprising a connection block, terminals

thereon for the resistance coils of the heating appliance, means for mounting said block on the heating appliance, in combination with an independent switch base having an extension adapted to overlie and embrace 60 said terminal block, flexible straps extending beneath said base, and means for connecting the same on the one hand to the terminals of the switch, and on the other hand to the 65 terminals of the block.

4. A switch for electric heating appliances comprising a connection block, terminals thereon for the resistance coils of the heating appliance, means for mounting said block on the heating appliance, in combination with an independent switch base recessed on its lower face to accommodate said block, and means for connecting the terminals on the block to the terminals of the 70 switch.

5. A switch for electric heating appliances comprising a connection block, terminals thereon for the resistance coils of the heating appliance, means for mounting said block on the heating appliance, in combination with an independent switch base recessed on its lower face to accommodate the block, straps located on the lower face of said block and connected on the one hand to the switch terminals and extending, on the other hand, 75 into register with the terminals on the block, and means passing through the switch base to establish electrical connection between 80 said straps and the terminals on the block.

6. A switch for electric heating appliances comprising a connection block, terminals thereon for the resistance coils of the heating appliance, means for mounting said block on the heating appliance, in combination with an independent switch base recessed on its lower face to receive the block, means for electrically connecting the switch terminals with the terminals on the block, and means for securing the switch base to the heating 85 appliance, said base serving to retain the 90 terminal block in assembled position in the 95 appliance.

7. In an electrical heating appliance, an apertured frame member, a terminal block mounted thereon and connected to the resistance units of the appliance, in combination with an independent switch base, means for mounting the same on said appliance in position overlying the terminal block, and means for establishing electrical connection 100 between the terminals on said block and the 105 terminals of the switch.

In testimony whereof I have signed my name to this specification.

HOYT CATLIN.
